UNITED STATES PATENT OFFICE.

HELENA S. SADTLER, OF SPRINGFIELD TOWNSHIP, MONTGOMERY COUNTY, PENNSYLVANIA.

SMOCKING-PATTERN.

1,377,631.

Specification of Letters Patent. Patented May 10, 1921.

Application filed May 1, 1915. Serial No. 25,181.

To all whom it may concern:

Be it known that I, HELENA S. SADTLER, a citizen of the United States, and a resident of Springfield township, Montgomery county, State of Pennsylvania, have invented certain new and useful Improvements in Smocking-Patterns, of which the following is a specification.

My invention relates to improvements in smocking patterns in which suitable markings or indicia are provided which may be employed to indicate the points at which the stitches should be taken in a flat fabric so that without any preliminary folding or 15 plaiting the smocking design may be directly formed, the material being simultaneously folded and plaited.

In the art of smocking, as far as I am aware, it heretofore has been the practice 20 in the production of smocking patterns to arrange dots upon a suitable sheet of material, as paper, in rectangular relation to each other, the dots being arranged in vertical and horizontal rows substantially at 25 right angles to each other and the dots in each row being in alinement. In the use of such smocking patterns these dots have been transferred in any suitable or known manner to the material to be smocked after 30 which the material is folded on the lines of the vertical dots by means of drawing threads passed through the dots in horizontal direction after which the smocking figures are worked upon the folded or 35 plaited fabric by inserting the stitches at suitable points upon the crests or apices of the folds, such points being determined by the eye without the aid of indicating dots or other indicia. As a result it has been 40 impossible to produce a finished design of smocking work having that exactness of alinement, shape and configuration which is desirable for the production of the best effects.

45 The purpose of my invention is to overcome these objections and to provide a pattern having dots or other indicating means situated thereon in such positions that when corresponding positions have been indicated 50 upon the material which is to be smocked the points at which the needle is to be inserted and at which the folds are to be formed are indicated thereon rendering unnecessary the preliminary step of folding 55 the material which heretofore has been nec-

essary before the smocking stitches could be formed upon the material.

In the carrying out of my invention patterns having different arrangements of dots or other indicating means thereon may be 60 made, such dots or other indicating means being so arranged that when an article is smocked by forming the stitches in accordance with the positions indicated by the dots or other indicating means upon the pattern 65 different designs will be produced conforming to the plan of the design and producing the effect which was intended to be produced by the arrangement of the dots or other indicating means upon the pattern. 70

In order that my invention may be more easily and fully understood reference should be had to the accompanying drawing in which I have illustrated a convenient embodiment of my invention. 75

In the said drawing:—

Figure 1 is a plan view of a portion of a pattern sheet having one design of dots thereon; and

Fig. 2 is a view showing a section of flat 80 fabric, a portion of which has been stitched or smocked in accordance with the pattern shown in Fig. 1.

Referring to the drawings, 1 designates a sheet of suitable material, such as paper, 85 having thereon a plurality of dots arranged with respect to each other as shown. It will be understood that these dots may be arranged otherwise with respect to each other so that the design of the stitched or 90 smocked material may be varied as desired.

In Fig. 1 of the drawings I have shown the dots in lines 2, 3, 4 and 5 in horizontal alinement while the dots in lines 6, 7 and 8 are out of horizontal alinement. 95

In the pattern as illustrated the dots thereon are formed of transferable material so that they may be transferred from the pattern on to the flat material, such as fabric, to serve as a guide to the person who 100 does the work of smocking upon such material.

The dots upon the pattern sheet 1 are arranged in a plurality of rows substantially at right angles to the rows 3, 4 and 5 and 105 those in each vertical or right angular row are in substantial alinement.

Referring to the row 6 it will be observed that the dot *a* is situated in a horizontal line below the dot *b* and also below the dot *c* 110

and in alignment with the dot *d*. Referring to the row 7 it will be observed that there are a series of dots in opposing relation to the dots *a b c d* and that the dot *e* is in a horizontal line above the dot *f* and also above the dot *g* and is in alignment with the dot *h*. This grouping and arrangement are repeated successively throughout the lines 6 and 7. In the construction shown the 10 horizontal distance between the dots *a* and *b*, *b* and *c*, *c* and *d*, and between *e* and *f*, *f* and *g*, and *g* and *h* is approximately one-fourth of an inch while the vertical distance up or down between the dots *a* and *b* and 15 *e* and *f* is substantially one-eighth of an inch. The same relation exists between the dots *c* and *d* and *g* and *h*. While the horizontal distance between the dots may be varied within reasonable limits the step up 20 or step down should in all cases be substantially one-eighth of an inch. Instead of sewing a single step up or a single step down as illustrated there may be a plurality of steps up or down. In such case the horizontal 25 distance between the successive dots should be uniform and may be, as already indicated, either one-fourth of an inch or a distance greater or less within reasonable limits. The step up or step down, however, 30 between successive dots should not vary substantially from one-eighth of an inch. The distance apart horizontally of the dots in the rows 2, 3, 4 and 5 is the same as the horizontal distance between the dots in the 35 rows 6, 7 and 8.

When the dots upon the pattern have been transferred to a fabric they indicate to the seamstress the points at which the stitches should be taken. In actual practice, the 40 needle should be inserted from the under side of the fabric through a dot at what may be termed the beginning of the pattern at the left hand side, the thread being retained in the material by means of a knot formed in 45 the end thereof in the usual manner. Thereafter the needle should be inserted downwardly through the material at a point a short distance to the right of each dot and then upwardly through the material and 50 through the adjacent dot. A slight pull upon the thread away from and substantially at right angles to the loop just formed will cause the folding and puckering of the material at the points desired and when the 55 stitches have been formed at the several dots outlining the pattern the result will be that the material is properly folded and a design formed by the thread conforming with and corresponding to the design of the 60 pattern employed. Although I have stated above that the needle should be inserted at a point a short distance to the right of each of the dots it is to be understood that the same result may be obtained by inserting the 65 needle downwardly through each dot and

causing it to emerge upwardly through the material at a short distance to the left of each dot. The essential fact or consideration is that the dots indicate to the seamstress or operative where the stitches are to be made and also enable the stitches to be made in uniform relation with respect to each other so that the smocking design sought to be produced will inevitably result if the pattern be followed. 70

It will be understood that instead of dots other indicating means may be employed so that the design of the pattern may be placed upon the sheet of material to be smocked. It will also be understood that the pattern 80 design may be printed directly upon or otherwise placed directly upon the sheet of fabric upon which the smocking design is to be worked.

In Fig. 2, 10 designates a flat piece of 85 suitable fabric including a portion which has been worked or smocked in accordance with the pattern design illustrated in Fig. 1. The rows of stitches 11 have been formed by following the lines of dots 2, 3 and 4 shown 90 in Fig. 1, the loops of the stitches being alternately thrown above and below the horizontal lines of said dots. As the thread is drawn through the material it is given a pull away from and transversely of the loop just 95 formed thereby of sufficient force to fold the material as indicated so that a design such as is illustrated is produced. The rows of 100 stitches 12 and 13 are formed by stitching the material in accordance with the dots 105 shown in line 6 and 7 on the pattern sheet 1. It will be observed that the stitches formed in accordance with the rows of dots 6 and 7 constitute diamond-shaped figures, the upper 110 and lower apices of the said figures being formed by inserting the needle through the material in the manner indicated above and by drawing the portions of material at the dots *b* and *c* and *f* and *g* toward each other, as indicated.

In sewing from a dot *a* to a dot *b* the 115 needle thread is held below the horizontal line of the stitches while in going from a dot *b* to a dot *c* and from the latter to a dot *d* the needle thread is held above the horizontal line of the stitches; that is, whether in line 6 or line 7 in taking a step up the thread is held below the horizontal line of stitches while in taking a step down the thread is held above the horizontal 120 line of stitches.

The row of stitches 15 shown in Fig. 2 is spiral and is formed on the line of dots 5.

By forming the stitches to conform to the dots in the row 8 an angular line of stitching 125 16 is formed as indicated in Fig. 2 of the drawing.

The appearance of the design may be varied by using thread of different colors and it may be varied also by changing the stitch 130

as may be seen by comparing the appearance of the stitches 11 and 15. It will also be understood that the pattern design may be varied as desired.

5 I claim:—

1. A smocking pattern comprising a sheet of suitable material having thereon indicating means consisting of separate elements and the said pattern comprising rows of said 10 indicating means which indicating means in the said rows is out of alinement, the relation of the separate elements of the said indicating means in each row determining the design of the respective rows of stitches 15 corresponding to the rows of indicating means.
2. A smocking pattern comprising a sheet of suitable material having thereon a plurality of horizontally and vertically arranged rows of indicating means consisting of separate elements the said vertical rows of indicating means being in alinement and the indicating means of some of the horizontal rows being out of alinement, 20 25 the relation of the separate elements of the

said indicating means in each row determining the design of the rows of stitches corresponding to the said rows of indicating means.

3. A smocking pattern comprising a sheet 30 of suitable material comprising rows of horizontally arranged dots the said dots in said rows being out of alinement with each other, each row of dots indicating the line of a complete and continuous row of stitches. 35

4. A sheet of material having thereon means to indicate the positions at which stitches are to be taken to produce a smocking design, said indicating means comprising horizontally arranged rows in which 40 portions of said indicating means therein are out of alinement with other portions thereof.

In testimony that I claim the foregoing as my invention I have hereunto signed my 45 name this 30th day of April, A. D. 1915.

HELENA S. SADTLER.

In the presence of—

CYRUS N. ANDERSON,
FLORENCE DEACON.
